UNITED STATES PATENT OFFICE.

WALTER B. BURROW, OF NORFOLK, VIRGINIA.

APPARATUS FOR CASTING METALS IN VACUUMS.

SPECIFICATION forming part of Letters Patent No. 755,842, dated March 29, 1904.

Application filed July 2, 1902. Serial No. 114,094. (No model.)

To all whom it may concern:

Be it known that I, WALTER B. BURROW, a citizen of the United States, residing at Norfolk, in the county of Norfolk and State of Virginia, have invented a new and useful Apparatus for Casting Metals in a Vacuum; and I declare the following to be a full, clear, and exact description of the same.

My invention relates to flasks or molds for casting metals in a rarefied atmosphere formed within the apparatus, thereby removing the air and gases from the mold and producing sound castings free from blow-holes, cavities, and other defects.

Referring to the drawings, Figure 1 is a sectional end elevation of the apparatus, taken on the line 2 3 in Fig. 3. Fig. 2 is an elevation of the complete flask or box. Fig. 3 is a plan of the apparatus. Fig. 4 is an elevation of one of the plugs or stoppers and is used to check the inrush of air into the mold, as will be herein-after described. Fig. 5 is a partial plan of the flare end or flange on the outside drag or box and the metallic seal; also, a section of the lower end or flange of the outside cope or top, taken on the line 1 in Fig. 1.

In the drawings, in which like letters of reference indicate similar parts in all the views. A is the outside drag or box.

B is an angular sealing-flange around the drag A, which tapers to form a flared projection or rim.

C is the outside cope, bonnet, or top, containing two or more tubes or pipes through it, as shown in Fig. 1. The tubes or pipes C' and T are preferably cast with the cope C, or the lower part may be cast and the upper end screwed into the cope or top.

E represents vents in the mold to allow the escape of the air and gases therefrom.

F is the ordinary flask containing the mold and is placed inside of the outer drag A and the cope C, which entirely incloses it, as shown in Fig. 1.

G is a sand filling over the water or air space R between the outside drag A and the flange O of the cope or bonnet C.

H is a fusible metallic seal poured on top of the sand filling G, forming an air-tight joint between the two parts A and C.

I represents guide-pins around the flange B of the outside drag A for the registering of the cope C upon it.

J represents the taper upper ends of the funnel-tubes C' and T for the insertion of plugs, as will be hereinafter described.

K is the sand mold of the casting in the flask F and inclosed by the outside cope and drag, as in Fig. 1.

L is a vacuum-pipe for withdrawing the air and gases from the cope C, the drag A, and the mold K.

M, Fig. 1, represents plates upon which the sand filling G and the seal H are supported in position and are located between the inner flask F and the outside drag A. The plates M are used when the space R is filled with water for cooling the various parts. In ordinary cases rubbish, such as cinder, can be used in place of the water up to the plates M. In small molds the entire spaces G and R can be filled with sand. The plates M are placed around the drag A, as shown by dotted lines in Fig. 3.

N is a plug for an opening to test the vacuum within the apparatus.

O is a flange on the cope C, extending downward into the sand filling G and against which the metallic seal H is placed.

P is the runner or riser of the mold K.

Q is the tapered lower end of the funnel-tube C', which is inserted into the opening P of the mold K.

R is the water or air space around the mold-flask F.

S is one of the plugs for the funnel-tubes C' and T, U being the head of the plug, and V an asbestos packing ring or gasket for maintaining a tight joint between the plug and the funnel-tubes.

The operation of the apparatus is as follows: The mold K in the flask F is placed in the outside drag or box A, and the outside cope or bonnet C is carefully placed over the box A, so that the funnel-tubes C' and T will enter the riser and runner of the mold, as shown at Q in Fig. 1. The cope C is guided and kept vertical by the pins I on the flange B of the drag A. The plates M are then secured in position and the sand filling G placed

on top of them, or the entire spaces G and R can be filled with sand, according to circumstances. The projection or flange O of the cope or bonnet C is then pushed downward 5 upon the sand filling G and made level. The sand is then tucked firmly around the flange O and the drag A, so as to keep the cope C from settling to one side and damaging the mold. A fusible metal or alloy in a molten 10 state is next poured upon the top of the sand filling G between the cope-flange O and the drag A, which firmly joins the two, making an absolutely air-tight seal or joint. The space R can be filled with cinder, broken 15 brick, and the like and the sand packed upon it, or all sand may be used, as already described. The space R is adapted for the circulation of water when the seal H is in danger of being softened or melted by the heat 20 in the case of large steel castings, though in ordinary foundry-work a sand filling will in all probability be sufficient. The mold is well vented upward into the cope C, under which the air and gases in the mold ascends to be 25 drawn off by means of the pipe L, connected to a vacuum-pump or other means. After the seal H is applied the metal is poured into one of the funnel-tubes C' or T until it rises to within two or three inches in the other, after 30 which the plugs S are loosely inserted into the tubes and the exhaustion commenced. After the metal is allowed to rest for a few minutes the plugs are driven in tightly and the rarefaction continued until the metal shows 35 signs of solidifying, at which point the connection between the pipe L and the pump is broken and the apparatus allowed to stand until cold and the flask taken apart by melting the seal H or separated forcibly from each 40 other. The metal should be well up in the funnel-tubes C' and T, so that they may act as traps or reservoirs to supply any sinking of the metal in the mold.

Heretofore the methods that have been tried 45 for vacuum-casting have been defective, as the apparatus could not be made air-tight.

The pressure of the atmosphere on the metal in the funnel-tubes C' and T tend to pack the metal firmly into the mold. By venting the 50 mold perfectly the air and gases can be withdrawn after the metal is poured.

My invention can be modified to pour the molten material into a vacuous space previously formed in the box A and C.

55 The arrangements experimented upon by others have not given good results, because a cheap and perfect seal between the several parts could not be obtained, besides the devices have been too expensive.

60 When the funnel-tubes C' and T are sufficiently high, the head of the liquid metal and the atmospheric pressure will make a more solid casting than is possible without my apparatus.

65 In my invention no air can leak into the

mold or flask from the outside except through the tubes C' and T, and when they are full of the molten metal the apparatus is absolutely air-tight.

The seal H is both cheap and effective and 70 easily applied and removed.

The cope or bonnet C contains two or more tubes and sometimes only one; but generally two are all that are required, one being in that case a riser and the other a runner, as shown 75 at C' and T in Fig. 3.

Having described my invention, what I claim is—

1. A vacuum casting apparatus, the combination of a metallic outer drag, box or case, 80 a flange or lip projecting outward forming a flared rim at the top of the said drag, a detachable cope, bonnet or top over and entirely inclosing the mold in its flask or box, the said outer cope or top fitting into a space on a sand 85 filling around and between the inner mold-flask and the outer drag or box, and a metallic seal at the junction of the outer cope or top and the outer drag or box, of a lower melting-point than the said top part or cope and the 90 lower part or drag, as described.

2. A vacuum casting apparatus, the combination of a flanged outer drag, box or case, a cope, bonnet or top, detachable from the main body or lower part or drag, the said outer 95 cope and drag inclosing the mold, a metallic seal poured in while molten upon a sand filling between the outer drag or box and the outer cope or bonnet, forming a hermetically-sealed joint between the said outer cope and 100 drag, and tubes or pipes passing through the outer cope, bonnet or top, placed vertically upward at right angles to the plane or level of the top of the cope or bonnet and extending downward into the inner flask and mold, and 105 means for adjusting the lower ends of the said tubes to fit into the runner, riser or sink heads of the inclosed mold for the guidance of the metal therein, as described.

3. A vacuum casting apparatus, the combination of a flanged projecting flared-rim drag, 110 box or case, a detachable cope, bonnet or top, a metallic seal at the junction of the said cope and drag, and tubes upon the said cope or top, extending vertically up and down, the lower 115 ends of the said tubes fitting into the risers and runners of the inclosed mold and the upper ends acting as funnels for pouring the molten metal into the said mold, and refractory packed metallic plugs or stoppers, for 120 closing and opening the funnel-tubes, and an outlet-pipe for removing the air and gases from the said mold and the outer cope and drag, as described.

4. A vacuum apparatus for casting metals, 125 the combination of a flanged detachable interlocking cope and drag, a metallic seal around the junction thereof, and guide or funnel tubes for filling the mold with the molten metal, and removable plugs for closing the 130

upper ends of the said tubes to regulate the degree of rarefaction in the apparatus, a water jacket or space around the flange of the outside drag or case and the lower part of the 5 cope or bonnet and under the metallic seal to prevent its fusion, and a sand filling or sub-seal, between the said metallic seal and the water-space, substantially as described.

In testimony whereof I have signed my name to this specification in the presence of two sub- 10 scribing witnesses.

WALTER B. BURROW.
